UNITED STATES PATENT OFFICE.

WILLIAM CORBETT, OF SMITH'S FALLS, ONTARIO, CANADA.

GRAVE-VAULT.

SPECIFICATION forming part of Letters Patent No. 323,917, dated August 11, 1885.

Application filed May 23, 1885. (No model.)

To all whom it may concern:

Be it known that I, WILLIAM CORBETT, a subject of the Queen of Great Britain, residing at Smith's Falls, in the Province of Ontario and Dominion of Canada, have invented 5 certain new and useful Improvements in Grave-Vaults, of which the following is a specification.

This invention relates to improvements in 10 vaults or boxes for the reception of burial caskets or coffins; and the invention consists in the means and construction hereinafter described, whereby such vault or box is rendered more proof against the invasions of 15 grave-robbers, and also in preventing the escape of foul gases and odors from putrefying bodies in case of a too shallow burial.

In the accompanying drawings, in the several figures of which like parts are denoted 20 by similar letters of reference, Figure 1 is a top plan view of the vault; Fig. 2, a longitudinal section on the line $x-x$; Fig. 3, a transverse sectional view on the line $y-y$. Fig. 25 4 is a detail perspective of the spring-hinge catch. Fig. 5 is a detail perspective of my improved catch-holding lug. Fig. 6 is a detail perspective of the spring used in the catch.

The letter A designates the outer casing, 30 which may be constructed of any suitable material. B indicates an inner metallic lining for said case. C is a lid also having a lining or facing of sheet metal. This facing or lining is preferably secured by counter- 35 sinking bolts into the material of the outer casing and lock-nut on the inside, or I may use clinched nails for this purpose. To the under side of the lid C I secure, after suitable arrangement, a number of what I have 40 designated "spring hinge-catches." Each of these catches, (as best shown in Fig. 3,) consists of a slotted plate, a, and hooked arm b, hinged together at c. The hinge c is preferably a stop-hinge to prevent the arm b 45 from standing away from the plate a at an angle greater than a right angle. These catches are secured to the lid by means of screw-bolts d passed through the metal facing of the lid and the slots in the plate a and 50 curved spring a', all being held together by the nuts d'. The end of the spring a' presses against the hook-arm b, and tends to throw it outwardly. The hook-engaging lug, as shown in Fig. 4, consists of a cylinder or 55 tube, l, having a longitudinal slit, e', and se-

cured or cast with it the slotted fastening-plates d. At the lower end of this tube or cylinder is an inclined plate, e''. This catch-holding lug just described is an improved and preferred form; but it may be modified, 60 or any of the known lugs suitable for the purpose may be employed. By forming these parts with the slots for passing the securing-bolts through they may be nicely adjusted.

When the parts of the vault herein de- 65 scribed are secured in place and ready for use, the lid is applied by placing the same upon the top of the box in such manner that the catch-arms b will pass down through the tube e of the catch-holding lug and be thereby 70 guided up the inclined catch-plate, and when the lid is completely down the spring will force the hook beneath the catch and thereby secure the lid from removal.

Any kind or any degree of thickness of 75 metal may be employed; but that kind which will withstand the action of the elements with which it comes in contact is preferred.

It will be seen that access to the casket or coffin when the lid of the vault is once in 80 place is exceedingly difficult, and by means of the adjustability of the lid-securing means the lid can be made to fit very closely upon the vault, thus preventing the rapid escape of 85 foul gases.

Instead of the spring hinge-arm herein de- 90 scribed I may use, in connection with my im- proved hook-holding device, a hook-arm made rigid with its fastening-plate.

What I claim as my invention, and desire 95 to secure by Letters Patent, is—

1. The improved spring hook-catch for se- 100 curing the lid of a burial vault or casket, consisting of a slotted plate for securing the same to the lid, a downwardly-extending hook-arm hinged to said fastening-plate, and a curved slotted spring secured to the slotted arm of the spring-hook and having its free end bearing against the hook-arm, as shown and described.

2. The improved catch-holding lug herein 105 described, consisting of the tubular portion e, with the longitudinal slit e', the inclined hook-catch plate e'', and fastening-plates d, substantially as shown and described.

In testimony whereof I affix my signature in presence of two witnesses.

Witnesses: WILLIAM CORBETT.
